APPARATUS FOR THE COUNTING OF SHEETS OF PAPER, ESPECIALLY BANK NOTES

Kristian Holmen, Oslo, Norway

Application May 31, 1955, Serial No. 512,106

Claims priority, application Norway May 29, 1954

4 Claims. (Cl. 271—27)

The present invention relates to apparatus for the counting of sheets of paper, especially bank notes, and is designed to provide a counting apparatus which, without being particularly expensive in manufacture, has an extremely large counting capacity.

A further purpose of the invention is to provide a counting apparatus which is suitable for the counting, not only of new bank notes, but also of used ones. This must be taken into consideration in choice of design for the apparatus, because used notes are often more or less damaged, for instance they frequently lack one or more of their corners.

Several forms of apparatus for the conveying of sheets of paper from a pile to a printing machine or the like are known. Such an apparatus can theoretically also be used as a counter, by providing it with ordinary counting machinery, if such is not already fitted. But owing to the fact that such an apparatus has a different purpose, it will not be suitable for the purpose, for example, of counting bank notes. Apparatus for the feeding of printing machines with paper take up large space and work at relatively slow speed. In the solution of the problem which forms the basis of the present invention, it must be noted that the aim is not to bring about any substantial change in the position of the bank notes, but to attain the maximum speed of counting. This does not prevent, in the construction of a counting apparatus, the employment of units and principles which in and by themselves are familiar from apparatus for the conveyance of sheets of paper.

Thus in the apparatus according to the present invention use is made of a rotary gripper which carries a number of symmetrically arranged suction organs, which besides rotating on the axis of the gripper rotate individually in the opposite direction on their own axis parallel to the axis of the gripper, and which are caused to rest one at a time against a sheet (bank note) near one of the edges of this, and by suction force to draw this along with it. Such a construction has previously been proposed and in this known arrangement the sheet is drawn up from a pile, the edge of the sheet being carried round by the suction organ until it strikes against a conveying roller. The sheet is given a relatively complicated movement, the whole sheet being drawn from the outside into the gripper, i. e. onto that side of the suction organs which faces the axis of the gripper, and is then conducted out again by a movement in the plane of the sheet. Unlike this known arrangement, the apparatus according to the present invention works in such a manner that the bank note is released after such a brief angular movement of the suction organ that the sheet is practically only swung round the edge which is turned away from the suction organ, without being moved in its plane. To prevent the note from swinging back to its initial position, the distance between the suction organs is suitably made so small that when a note is released from a suction organ the following suction organ will prevent it from swinging back.

2

The invention is described in greater detail in connection with the accompanying drawing, in which:

Figure 1 shows in diagrammatic form a gripper for an apparatus, viewed from the end, with a suction organ resting against the first note in a bundle of notes to be counted,

Figure 2 shows the gripper after rotating through about 36°,

Figure 3 shows the gripper after a further rotation of approximately 108°,

Figure 4 is a vertical section through one of the suction organs and the apparatus on which it is mounted.

Referring to the drawings, A1—A5 denote five individually rotatable cylindrical suction organs arranged on a rotating gripper, which in Figures 1 to 3 is only indicated by the hollow axle B. It will be sufficient to state that the gripper rotates anti-clockwise, as indicated by the arrow b, while the suction organs revolve in the opposite direction, as indicated by the arrows a.

As will be seen from Figure 4, the gripper includes a central spindle 1 to which is secured by a nut 2 a gear member 3 provided with internal teeth 4. The gear member 3 is bored to receive a suction tube 5 secured in the spindle 1, which tube 5 communicates with a source of suction (not shown) and is in permanent communication with an axial bore 6 in the spindle 1, which bore extends to a point near the top of the spindle to communicate with a transverse bore 7, which itself communicates with each rotary suction organ when the latter is in operative position for counting a bank note. Rotatably mounted about the spindle 1 on a bush 8 is a pulley 9. The bush and pulley are bored as at 10 and 11 respectively, to establish communication between the bore 7 in the spindle 1 and each rotary suction organ when in operative position for counting a bank note. The pulley 9 is also provided with five bores, each of which receives a rotary suction spindle 12 (only one of which is shown in Figure 4) which spindle rotates in a bush 13 fast with the pulley 9, each bush 13 and spindle 12 being bored at 14, 15 respectively, to establish connection between the source of vacuum and a central bore 16 in the suction spindle. This central bore communicates with the suction head 17 which is secured thereto by a grub screw 18, the suction head 17 itself being bored at 19 to communicate with the central bore 16 and also with the suction orifice 20, the surface of the suction head, adjacent the suction orifice 20, being flattened to present a plain surface to facilitate adhesion of a bank note thereto.

Each suction spindle 12 includes a cylinder 21 and a light piston 22 slidably mounted therein, which piston is under bias of a spring 23, to urge it towards the left, as shown in Figure 4. The piston rod 24 has a reduced end projection passing through the outer end wall of the cylinder.

The said reduced end portion of the piston rod 24 is adapted, when the piston 22 is moved to the right, as will hereinafter be described, to force an electric contact member 25 into contact with a further contact 26 to complete an electric circuit, to operate an electro-magnetic counting device, which is not shown, and which is of known construction, and forms no part of the present invention.

Coupled to the suction organ spindle 12 by means of a grub screw 27 is a pinion 28, which meshes with the teeth 4 on the gear member 3.

The apparatus functions in the following manner: The suction tube 5 is first connected to the source of suction, for example a pump, and the pulley 9 is connected by a driving belt (not shown) to the pulley of an electric motor (also not shown) which can be set in motion when desired. When operated, the motor drives through the belt the pulley 9, which rotates with its bush 8 around

the spindle 1. Rotation of the pulley causes simultaneously rotation of the suction organs around the spindle 1, and hence, by means of intermeshing between the pinion 28 and the teeth 4, causes the suction spindles 12 to rotate in an opposite direction to that of the pulley 9. During rotation of the pulley 9 bores 10, 11 and 14 are brought in turn into communication with the bore 7 of the central spindle 1, and thus with the source of suction connected to the pipe 5. When communication between the bores 10, 11 and 14 and the bore 7 is established, the suction orifice 20 of the rotary suction spindle 12 is in contact with a bank note to be counted, whilst the position of the rotary suction spindle 12 is such that its bore 15 is in communication with the bore 14, so that suction is thus applied to the said suction orifice 20. It will thus be apparent that the duration of suction on the suction orifice 20 is the period of time during which the bore 15 is in communication with the bores 14, 11 and 10 when these bores in turn are in communication with the bore 7 in the central spindle 1.

When suction is established at the suction orifice 20, air is first sucked therethrough momentarily before a bank note adheres to the surface of the suction head. As the suction spindle 12 revolves, with the bank note attached to its suction head, during the period when the suction is maintained (see Figure 1) the bank note will be moved as hereinafter described. Once the bank note is caused to adhere to the suction orifice 20, the suction force tends to create a vacuum within the suction system, the effect of which is to cause the light piston 22 to move against the action of its spring 23, so that the reduced end of the piston rod 24 closes the electric circuit, including the contacts 25, 26, and thereby operate the counting device. As the suction spindle 12 continues to rotate, communication between the bores 15 and 16 and the bores 14, 11 and 10 no longer exists; furthermore the bores 14, 11 and 10 are no longer in communication with the bore 7 as the pulley 9 continues to rotate. The effect is thus that the piston 22 is returned to its normal position by the spring 23 and the bank note is released from the suction orifice 20.

Referring now again to Figures 1 to 3, it will be appreciated from the above description that the suction organs A₁-A₅ arrive in turn at the position occupied by suction organ A₁ (Figure 1) with the suction opening C (that is to say suction orifice 20) turned towards a bundle of notes D at the same time as the suction opening is brought into connection with the vacuum source. The note D₁ of the bundle which note is nearest to the suction head will thereby be sucked firmly thereto, and be carried along with this to the position shown in Figure 2. Shortly afterwards the suction opening C in the suction organ A₁ is brought into connection with atmosphere (as described with reference to Figure 4) and the note is released before it has yet moved in any significant degree in its own plane. It is not released, however, before the next suction organ A₂ has approached the bundle of notes D so closely that the note D₁, in the event of its swinging back in the direction of the bundle, will strike against the suction organ A₂ and be pushed by this to the right. Figure 3 shows how the counted notes are gradually assembled in a new bundle E.

It will be clear from the above description and with reference to Figures 1 to 3 that the notes are not subjected to any significant movement in their own plane, but are only leafed over in the same way as the leaves of a book. It has been found that by this means it is possible to perform the counting at substantially greater speed than with any other known construction.

What is claimed is:

1. For the counting of sheets of paper or the like ar-

ranged in a bundle or pile, an apparatus comprising a rotary gripper, means providing a fixed axis, means for rotating said gripper in one direction about said fixed axis, a plurality of suction devices arranged symmetrically around said fixed axis, means providing individual axes for said suction devices, said individual axes being equidistantly spaced around said fixed axis, means for connecting said suction devices to said rotary gripper for rotation on said individual axes, means operative by rotation of said gripper for constantly rotating said suction devices about their axes in a direction opposite to the direction of rotation of said gripper, each suction device having a suction opening, the rotation of said gripper moving said suction devices successively into proximity with the sheets in one direction and the reverse rotation of said suction devices moving said suction openings relatively to a sheet of the pile adjacent said gripper in the opposite direction, means for connecting the suction opening of each successive suction device to a source of vacuum as each suction device has its suction opening in proximity to the adjacent sheet and for cutting off such suction as each suction device rotates to a predetermined extent on its own axis from such position to release the sheet picked up by such suction opening, said suction devices being so circumferentially spaced that upon the releasing of each sheet from one of such suction devices, the next following suction device will be interposed between the released portion of the sheet and the pile to prevent the sheet from swinging back to the pile.

2. An apparatus according to claim 1 wherein said means for connecting each suction device to a source of vacuum comprises a vacuum duct formed in said rotary gripper, an axial passage formed in each gripping device and communicating the one end with the associated suction opening, and means operative incident to rotation of each suction device on its axis for connecting said duct and the passage of such suction device to each other solely when the suction opening of such suction device is adjacent the pile of sheets.

3. An apparatus according to claim 1 wherein said rotary gripper is provided with a co-axial gear, said means for connecting each suction device to said rotary gripper comprising a spindle rotatively supported by said rotary gripper, and a pinion carried by each spindle and meshing with said gear.

4. An apparatus according to claim 1 wherein said rotary gripper is provided with a co-axial gear, said means for connecting each suction device to said rotary gripper comprising a spindle rotatively supported by said rotary gripper, and a pinion carried by each spindle and meshing with said gear, said means for connecting each suction opening to a source of vacuum comprising an axial duct formed in said rotary gripper, an axial passage formed in each spindle, each spindle having a radial opening communicating with the passage therein, said rotary gripper having a plurality of radial passages each co-axial with one of said radial openings to communicate therewith as the latter passes the associated radial passage.
